9028

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 14,830, dated February 26, 1884.

Application filed January 23, 1884. Term of patent 3½ years.

To all whom it may concern:

Be it known that I, SARAH JANE SHIELS, of the city, county, and State of New York, have invented and produced a new and original Design for a Pattern of a Miss's Costume, (numbered 9,028;) and I do hereby declare that the engraved prints accompanying this specification convey to any one accustomed to using paper patterns a clear understanding of how a garment made up by the pattern will appear.

The design shows a walking-skirt with an overdress that displays closely-fitted fronts, having buttons from the throat to a little below the waist-line and flaring widely below, a closely-fitted back exhibiting plaited fans in-

serted in the lower parts of its middle three seams, a standing collar, a lapel-collar displaying its ends shaped in points and meeting at the end of the closing, pocket-laps, and coat-sleeves.

What I claim as my invention, and desire to secure by Letters Patent, is—

The design for a miss's costume, as shown in the engraved prints accompanying this specification.

SARAH JANE SHIELS.
